HAND SAW

Russell D. Knapp, 169 W. Cedar St., Elko, Nev. 89801

Filed Mar. 23, 1966, Ser. No. 1,596

Term of patent 14 years

(Cl. D93—4)

I claim:

The ornamental design for a hand saw, as shown.
